(57) **CLAIM**

The ornamental design for a control panel for generator, as shown and described.

DESCRIPTION

FIG. 1 is a perspective view of control panel for generator showing my new design.

FIG. 2 is a top view thereof.

FIG. 3 is a bottom view thereof.

FIG. 4 is a front end view thereof.

FIG. 5 is a rear end view thereof.

FIG. 6 is a left view thereof; and,

FIG. 7 is a right view thereof.
